SYSTEM FOR PRODUCING ULTRAVIOLET RADIATIONS

Willis O. Prouty, Hermosa Beach, Calif., assignor,
by mesne assignments, to Proutyline Products
Co., Manhattan Beach, Calif., a corporation of
California

Application August 17, 1931, Serial No. 557,601

3 Claims. (Cl. 250—34)

This invention relates to a system for generating or producing ultraviolet radiations. More particularly it relates to such a system that utilizes a luminous tube having a filling of a noble 5 monatomic gas.

Such tubes have been described in several of my prior applications, which may be identified as follows: Therapeutic light, Ser. No. 448,128, filed April 28, 1930; Ultraviolet light source, Ser. 10 No. 524,649, filed March 23, 1931; and Hand supported ultraviolet device, Ser. No. 529,698, filed April 13, 1931.

In such tubes, a filling of neon, argon, helium or the like or mixtures thereof is used at a pressure of the order of from four to twelve millimeters of mercury. To enhance the effect of the 15 radiations, a drop or two of mercury can also be sealed into the tube, which is of course made from some material such as quartz that can pass the 20 ultra-violet radiations.

Such tubes employ relatively high voltages of the order of a thousand volts, and small current consumption. In my prior applications, I describe how it is possible to secure intense radiations having great therapeutic or germicidal value 25 by a comparatively low current consumption, and thereby keeping the tube so cool as to be readily manipulated by the operator without artificial cooling.

30 It is one of the objects of my invention to provide a compact and portable power supply system for such tubes.

It is another object of my invention to provide a portable system that can be readily attached 35 or detached with respect to a commercial alternating current supply, and that can be used interchangeably with any one of a number of different types of tubes. In this way, for example, a general treatment can be given by a tube that emits 40 the radiations over a comparatively large area; or alternatively, an orificial unit can be used, which can be readily applied to any of the various cavities or orifices of the body, such as in the nostrils, mouth, or ears.

45 My invention possesses many other advantages, and has other objects which may be made more easily apparent from a consideration of several embodiments of my invention. For this purpose I have shown a few forms in the drawings accompanying and forming part of the present specification. I shall now proceed to describe 50 these forms in detail, which illustrate the general principles of my invention; but it is to be understood that this detailed description is not to be 55 taken in a limiting sense, since the scope of my

invention is best defined by the appended claims.

Referring to the drawings:

Figure 1 is a perspective view of a portable system embodying my invention;

Fig. 2 is a plan view thereof;

Fig. 3 is a wiring diagram of the system;

Fig. 4 is a perspective view of a dental cabinet type embodying my invention;

Fig. 5 is a front view thereof; and

Fig. 6 is a bottom plan view thereof.

In Figs. 1 and 2 I show an apparatus that is housed conveniently in a portable suitcase type of container. The container thus includes the main case 11 and a hinged cover 12. The case 11 can have a handle 13 and can be provided with one or more locks 14.

The case 11 has provisions for housing one or more radiating tube devices, such as 15, 16. This can be accomplished by forming appropriate depressions 17, 18 in a shelf 19 near an edge of the case 11. The shelf and depressions can be lined with some soft fabric such as velvet. A retainer piece 20 can be fastened to the inside of cover 12 to engage these devices 15, 16 when the case is closed, and thus prevents jarring during transportation.

Device 15 includes a casing having a window 21 through which is exposed a quartz tube 22 (Fig. 3) filled as before stated, at from about four to twelve millimeters of mercury, with a noble monatomic gas, or a mixture thereof. The casing also serves as a convenient handle. The tube furthermore, preferably has a bore no larger than seven millimeters in diameter. As pointed out in my prior application, Serial No. 524,649, the small 90 diameter reduces very materially the absorption of the useful rays, because the radiations pass through only a narrow layer of intervening gas before reaching the exterior of the tube. Furthermore, full brilliance is obtained with a current flow of thirty milliamperes, or not more than fifty milliamperes, so that the tube stays cool. The casing 15 can thus be handled without any artificial cooling. This casing of course is appropriately insulated from the terminals of tube 100 22.

Device 16 has the same general characteristics. The tube 23 however is not covered by the casing but is exposed so that it may be inserted into a cavity or orifice. This device can be built 105 in accordance with the specifications in my pending application, Serial No. 529,698. In general, it comprises an inner and an outer tube, and a pair of electrodes extending respectively into the inner tube and into the annular space be- 110

tween the tubes. This device 16 can also be provided with prongs such as 24 to lead current to the gas column.

By providing small tubes and the proper electric 5 tromotive forces, the ultraviolet radiations can be made intense at and neighboring the most effective frequencies for germicidal purposes. Thus an intense radiation is obtained by my device in the region of the light spectrum at and near 2536 10 Angstrom units; and the radiations are generally within the limits of from 3100 Angstrom units down to about 1800 Angstrom units.

I shall now describe how either of the devices 15, 16 can be energized by means of apparatus 15 enclosed in the case 11. Thus adjacent the rear of this case, a compartment 26 is formed that houses a step-up constant current transformer 25 (Fig. 3). The primary winding 26' of this transformer is adapted to be detachably connected 20 to any light socket or the like, as by a flexible twin lead 27. This lead carries the usual plug 28 and can be made as long as convenient. It enters into the vertical wall of compartment 26, through an insulation bushing 29. The secondary 25 winding 30 of the transformer 25 can be grounded, as shown at 31 (Fig. 3) and is connected as by a heavily insulated twin conductor cable 32, to a twin receptacle 33. This cable extends through the vertical wall of compartment 26. The receptacle 33 is arranged to accommodate the 30 prongs such as 24, which are associated with devices 15, 16. In this way, either device can be energized as desired.

In order to ensure against any accidental improper grounding by any of the metal portions of the devices 15, 16, one of the prongs 24 can be grounded to these metal parts and is so arranged as to connect always to the grounded lead 34 (Fig. 3). This can be accomplished by making 35 the two prongs of different sizes or forms, so that they can enter corresponding differently formed socket portions in receptacle 33, and can never enter these sockets in any other order.

It is thus seen that I have provided a simple 45 detachable connection to any of a number of devices, any of which can be used at will.

Preferably the milliamper consumption in the tube should be indicated. This can be accomplished by including a milliammeter 35 in the 50 secondary circuit. This milliammeter can be set into the top wall of compartment 26. The complete secondary circuit can now be traced. It includes the coil 30, ammeter 35, one socket of receptacle 33, a prong on either device 15, 16, the 55 quartz tube 22 or 23, the other prong, receptacle 33, lead 34, back to the other side of coil 30.

In order to time the period of exposure automatically, a time switch 36 (Fig. 3) can be included in the primary circuit. This time switch 60 can be housed in compartment 26, with control levers projecting through for controlling it and for setting it. Thus, as shown in Figs. 1 and 2, a slotted plate 37 can be affixed to the top wall of the compartment 26. Through the slots in 65 this plate can project a setting lever 38 and a starting lever 39. Graduations 40 on the plate cooperate with a mark 41 on lever 38 to indicate the period that the switch will stay closed. Lever 39 winds up a clockwork mechanism and closes 70 a switch by being pulled to the right, and this also starts the timing function. Since such time switches are now well-known, further description is unnecessary except to state that after the set period of operation, lever 39 is released and 75 returns to the left hand position shown.

It is advisable to reduce the current flow when the official device 16 is used, as the tube portion 23 is intended to be placed in contact or nearly so with the tissues treated, and must be therefore kept still cooler than when full energization is used. The current consumption can be regulated by a high-low switch 42, (Fig. 3) also enclosed in compartment 26. This switch controls the number of turns active on the primary coil 26, the lower number being used when device 16 is in circuit. A hand lever 43 for controlling this switch extends out of the compartment 26.

The primary circuit can now be traced. From plug 28, the circuit includes switch 42, coil 26, time switch 36, to plug 28. When the levers 38, 39 are properly set, and device 15 or 16 properly plugged in, and with plug 28 in operative relation with an appropriate commercial source, the device 15 or 16 is rendered active and stays active until switch 36 operates.

The leads 27, 32 and devices 15, 16 can all be accommodated in case 11, and it can be closed and locked for ready transportation.

It is not necessary that the elements of the system be incorporated in a suit case type of container. Thus for example, for dental work, a wall casing such as shown in Figs. 4, 5 and 6 can be used.

In this case, the container 44 has a closed central portion 45 in which the transformer 25, time switch 36, the regulating switch 42, and ammeter 35 can be housed. This container can be hung on a wall in any appropriate location. Sockets 46, 47 can be provided in the bottom for connection respectively to a commercial source and to a heavy insulated cable such as 32. These connections are clearly shown in Fig. 5.

At each side of the closed portion 45 is a further compartment such as 48 (Fig. 4) that can be closed by a hinged door 49. When closed, these doors with compartment 45 present a pleasing ornamental appearance. On the vertical side of the compartment 48 one or more spring clips such as 50 can be provided for holding devices such as 15 or 16, as well as the detachable leads to be used therewith. The system has the same wiring as disclosed in Fig. 3 and operates in the same way.

I claim:

1. In an ultraviolet ray apparatus, a portable container having a closed compartment, a step-up transformer in said compartment, said transformer having a primary and a secondary winding, conductors leading from the primary winding, and through the wall of the compartment into the container, a detachable connector connected to the conductors for connecting the primary winding to a commercial alternating current source, a time switch in the compartment and in circuit with the primary winding, said time switch having a control member for starting it extending outside the compartment, as well as a time setting member also extending out of the compartment, high potential leads connected to the secondary winding and extending through the wall of the compartment into the container, a separable connection carried by said high potential leads, and a luminous tube device capable of being supported in the container and arranged to be optionally connected to the separable connection of the high potential leads, said device including a quartz tube, and a handle for the tube, said tube having a filling of one or more noble monatomic gases, said device also having means for leading the high potential current to the column of gas in the tube, the section 150

- of the tube being such that radiations in the ultra violet spectrum are generated thereby which are pronounced between 1800 and 3100 Angstrom units and have a maximum effect at and neighboring 2536 Angstrom units. 5
2. In an ultraviolet ray apparatus, a container having a closed compartment, a step-up transformer in said compartment, said transformer having a primary and a secondary winding, conductors leading from the primary winding, a detachable connector connected to the conductors for connecting the primary winding to a commercial alternating current source, a time switch in the compartment and in circuit with the primary winding, said time switch having a control member for starting it extending outside the compartment, as well as a time setting member also extending out of the compartment, high potential leads connected to the secondary winding, a separable connection carried by said high potential leads, and a luminous tube device capable of being supported in the container and to be separably connected to the separable connection of said high potential leads, said device including a quartz tube, and a handle for the tube. 80
3. In an ultraviolet ray apparatus, a container, a step-up transformer therein, said transformer having a primary and a secondary winding, conductors leading from the primary winding, a detachable connector connected to the conductors for connecting the primary winding to a commercial alternating current source, a time switch in the container and in circuit with the primary winding, high potential leads connected to the secondary winding, a separable connection carried by said high potential leads, and a luminous tube device capable of being supported in the container and arranged to be optionally connected to the separable connection of the high potential leads, said device including a quartz tube and a handle for the tube. 85
